G. MAZZA

RECIPROCATING ELECTRIC MOTOR

Filed April 12, 1921

Inventor
Guido Mazza,
By *Steampunk* Atty.

UNITED STATES PATENT OFFICE.

GUIDO MAZZA, OF TURIN, ITALY.

RECIPROCATING ELECTRIC MOTOR.

Application filed April 13, 1921. Serial No. 460,677.

To all whom it may concern:

Be it known that I, GUIDO MAZZA, a subject of the King of Italy, and resident of 24 via Ospedale, Turin, in the Kingdom of Italy, have invented certain new and useful Improvements in Reciprocating Electric Motors; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to reciprocating electric motors, more particularly for percussive tools, of the kind comprising an electro-magnet whose core is moved in one direction electro-magnetically and in the other direction by spring means.

The present invention consists of a reciprocating electric motor of the kind stated, characterized in that the casing of magnetic material for the coil of the electro-magnet is constituted by substantially C-shaped plates or strips spaced around the coil and engaging radial grooves provided in the outer surfaces of insulated end covers. This arrangement eliminates eddy or Foucault currents which tend to heat up the motor and, owing to the large surface of the coil exposed to the air, provides for effecting cooling of the inner parts.

The invention also consists of the novel construction and arrangement of parts in a tool equipped with my improved electric motor, including an automatic switch comprising movable contact blocks which are brought into and out of contact, during the reciprocating of the core of the electro-magnet, in such manner as to reduce sparking and to avoid all possibility of shocks to the operator.

A form of the invention as applied to a percussive tool or hammer is illustrated, by way of example on the accompanying drawing wherein:—

Fig. 1 is a longitudinal section of a mechanical hammer embodying my invention.

Fig. 2 is a cross section of same on line A, B, Fig. 1.

Fig. 3 is a diagrammatic sectioned view of the switch.

Fig. 4 is a detailed view of the switch.

The mechanical hammer is substantially constructed of a coil 14, arranged in a cage formed by end covers 16 of insulating material and C shaped plates 17 of magnetic material spaced equally around the coil and mounted in radial grooves provided in the outer surfaces of the insulated covers. A sleeve or liner 13 of suitable material is secured inside the coil and is closed at one end by the pole piece while at its other end it carries the core 23. The pole piece comprises a tool carrier 18 and a sleeve 19 constructed of plates of magnetic material connected to each other by means of riveting and soldering.

The tool carrier 18 slides with slight friction in the sleeve 19 and carries a cylindrical nut 20 for controlling the travel of the tool; said nut is movable in the cylindrical cavity 22 provided in the support 50 of the tool carrier connected with the casing 15. The sleeve 19 projects inside the coil for a suitable distance and the tool carrier 18 constructed of a cylindrical rod of magnetic material is fitted in the sleeve and projects outside this latter for a distance slightly exceeding the working motion. Said projecting portion carries a block of nonmagnetic and very hard material 51. The core 23 is movable longitudinally inside the coil 14 and is formed by a bundle of sheets of magnetic material riveted to each other. The sheet inner ends constituting the core are suitably soldered to each other in order to form a single block and the outer enlarged core end carries a conical axial recess 25 and an outer flange 26. A helical spring 27 resting on the upper horizontal ends of plates 17 and the flange 26 tend to force the core outside the coil. The casing 15 provided at its upper part with a handle 35 is divided by means of partitions 36 and 37 into three compartments communicating with each other through openings of the partitions. The lower chamber contains the coil 14; the central one the core head 38 and in the upper chamber is secured the automatic switch and an ordinary switch operated by hand by means of a stud 46. The switch is constructed of sectors of conductive material 39 and 40 secured to the insulating disc 41. One of the outer conductors 42 connects to one of said sectors, while the other sector is electrically connected to one

of the opposite leaf springs 32 secured to the plug 43 of insulating material. The other leaf spring is electrically connected with the coil 14, to which connects the other outer 5 conductor 42. Each of the axially disposed leaves 32 is provided at its free end with an outer insulating block 33 and at an intermediate point with a conducting block 34 secured to the leaf spring inner face. The 10 blocks 33 are so arranged in the core recess 25 that, when the core has reached the end of its motion outside the coil, they rest on the conical surface of the recess thus bringing the leaf springs 32 nearer and establishing 15 the contact between the blocks 34. The distance between the leaf springs is regulated by means of a wedge 53 secured at the end of a set screw 44, so that by winding or unwinding said screw, it is possible to place 20 said leaf springs at the distance required for a regular working. The ordinary switch is constituted by a conducting sector 45 arranged laterally of the sectors 39, 40 in such a way as to come into contact with said 25 sectors and move away from them by means of a rod 46 suitably mounted on the handle 35.

The contact blocks 34 of the automatic switch are protected by a plate 55 of suitable material and the core is provided with small openings through which the lower part of the recess communicates with the gap between the core and sleeve 13 allowing the lubricating oil to enter the recess and 30 lubricate the blocks 33.

To operate the tool the conductors 42 are connected to a suitable source of electrical energy; then whilst grasping the handle of the tool, the operator depresses the rod 46 thereby closing the switch sectors 39, 40 by means of the bridge piece or sector 45 (Fig. 3), and completing the circuit for the current through the coil 14 of the electromagnet whose core 23 is normally constrained by the 40 spring 27 to a position where the contact 34, 34 included in the circuit are closed. Immediately the coil is energized the core is drawn, against the action of the spring, towards the tool carrier or holder 18 so that it 45 contacts with the anvil-piece 51 and imparts a blow to the tool carried by the tool holder. At the end of the travel of the core in this direction the spring actuated contact 34, 34, move apart (permitted by the slight taper of the opening 25 in the core head) thus interrupting the circuit and de-energizing the coil whereupon the spring 27 acts to withdraw the core to its original position when the contacts are again closed 50 and the hereinbefore described operation is repeated so long as the operator presses down the switch rod 46.

Claims:

1. In a reciprocating electric motor, a 55 magnet coil, a casing for the latter comprising

ing a plate of insulating material at each end of the coil, and connecting members of magnetic material spaced around the coil and having end portions mounted in radial grooves formed in the end plates.

2. In a reciprocating motor, a magnet coil casing comprising two cover plates of insulating material having radial grooves formed therein, and connecting strips of magnetic material having angular end portions mounted in the grooves.

3. In a reciprocating motor, a magnetic coil, a core arranged to reciprocate therein and having a conical recess, an automatic switch comprising spring arms extending into the recess and contacts on said arms movable into and out of contact by the reciprocations of the core.

4. In a reciprocating motor, a magnetic coil, a core arranged to reciprocate therein and having an axially arranged conical recess formed in one end, an automatic switch comprising spring arms extending into the recess, insulating members interposed between the ends of the arms and the wall of the recess, and contacts on said arms movable into and out of contact by the reciprocations of the core.

5. In a reciprocating motor, a magnetic coil, a core arranged to reciprocate therein and having an axially arranged conical recess formed in one end, an automatic switch comprising spring arms extending into the recess, insulating members on the free ends of said arms normally engaging the wall of the recess, and switch contacts on said arms normally held in engagement by the arms.

6. In a reciprocating motor, a magnetic coil, a core arranged to reciprocate therein and having a conical recess formed in one end, an automatic switch comprising two contacts, spring arms carrying the latter and extending into the conical recess, said arms being operable by the wall of the recess to move the contacts into engagement means including the contacts to energize the coil to withdraw the core from the arms, and means to return the core into contact with the arms.

7. In a reciprocating motor, a magnetic coil, a core arranged to reciprocate therein and having a conical recess formed in one end, an automatic switch comprising two contacts, spring arms carrying the latter and extending into the conical recess, a spring for moving the core towards the arms to close the contacts, and means including the contacts to energize the coil whereby the core is moved against the action of the spring.

8. In a reciprocating motor, a magnetic coil, a core arranged to reciprocate therein and having a conical recess in one end, an automatic switch comprising two contacts,

spring arms carrying the latter and having their free ends extending into the recess, insulating members interposed between the free ends of the arms and the wall of the recess, a spring normally holding said wall in engagement with the insulating members to close said contacts, and means including the contacts to energize the coil to move the core against the action of the spring to open the contacts.

9. In a reciprocating motor, a magnetic coil, a core arranged to reciprocate therein, and having a conical recess in one end, an automatic switch comprising two electrical contacts, spring arms carrying the latter projecting into the recess and operable by the movements of the core to make and break the contacts, and a protecting plate

substantially surrounding the contacts, for the purpose specified.

10. In a reciprocating motor, a magnetic coil, a core arranged to reciprocate therein and having a conical recess in one end, two electrical contacts, spring arms carrying the latter projecting into the recess and operable by the movements of the core to make and break the contacts, a pair of switch plates, means electrically connecting one of the plates with one of the spring arms, means electrically connecting the other plate with the coil, and a hand operated bridge-plate for electrically connecting the plates to complete the circuit.

In testimony that I claim the foregoing as my invention, I have signed my name.

GUIDO MAZZA.
